[57] **CLAIM**

The ornamental design for a holder and grand anchor unit for cylindrical fence posts, as shown and described.

DESCRIPTION

FIG. 1 is a perspective view from the front, right side and above of a holder and ground anchor unit for cylindrical fence posts;

FIG. 2 is a left side elevation view thereof;

FIG. 3 is a front elevation view thereof;

FIG. 4 is a right side elevation view thereof;

FIG. 5 is a rear elevation view thereof;

FIG. 6 is a top plan view thereof;

FIG. 7 is a bottom plan view thereof;

FIG. 8 is a perspective view showing the top and front elevation view of a second embodiment of the unit illustrated in FIG. 1; and

FIG. 9 is a perspective view showing the top and front elevation view of a third embodiment of the unit illustrated in FIG. 1.

FIG. 1.

FIG. 6.

FIG. 7.

FIG. 2. FIG. 3. FIG. 4. FIG. 5.

FIG. 8.

FIG. 9.
